UNITED STATES PATENT OFFICE.

SAMUEL E. WITT, OF CHICAGO, ILLINOIS.

LOUD-SPEAKING RECEIVER.

Application filed August 12, 1924. Serial No. 731,603.

My invention relates to receivers and more particularly to loud speaking receivers of the type now generally employed in connection with radio apparatus, although of course, it is to be understood that it may be employed for any telephonic purpose where devices of this kind are employed.

An object of my invention is to provide an improved and simplified receiver of the character shown in my copending application for receiver, Serial Number 440,549, filed January 27, 1921, being of the so called direct current type.

There are various features to my invention, such as an improved adjustment for the magnet and armature carrying unit; the spool or coil construction; the unit construction; the method of locking the unit carrying frame to the base; the method of locking the cover to the base and of securing the horn to the device. There are various other features and these will be more particularly pointed out in the ensuing part of the specification and appended claims.

For a better understanding of my invention reference is to be had to the accompanying drawings, in which—

Fig. 1 is a side elevation of the assembled device with a cover and horn carrying parts in section to show the interior;

Fig. 2 is a sectional view through the receiver mechanism, also showing the method of locking the frame to the base;

Fig. 3 is a perspective detail view of the base lock and terminal carrying element;

Fig. 4 is an enlarged plan view of the coils and armature supporting bracket;

Fig. 5 is a sectional view along the line 5—5 of Fig. 4;

Fig. 6 is a side elevation of the apparatus unit removed from the cover with parts of the frame broken away;

Fig. 7 is a bottom view of Fig. 6, but with the base plate removed;

Fig. 8 is a top plan view of Fig. 6;

Fig. 9 is a right end view of Fig. 6; and

Fig. 10 is a left end view of Fig. 6.

Referring now more in detail to the preferred form of my invention as shown herein, it comprises a diaphragm holding member 15 made of suitable non-magnetic material and cupped so as to receive a diaphragm 16 between cushioning rubber rings 17 and held in place by a metal ring 18 forced into the recess. The metal along the

edge of the cup is then pressed inwardly in a suitable number of places 19, as indicated in Fig. 7, so as to hold the ring 18 and diaphragm in place.

A suitable frame for supporting the diaphragm cup 15 is provided, preferably in the form of two-legged members of similar construction, each one comprising two vertical legs 20 with the yoke portion 21 connecting the legs at the bottom and said legs being turned outwardly at the top and suitably secured to the diaphragm cup 15, preferably by rivets 22. Thus the diaphragm cup 15 and leg members 20 form a substantial base for carrying all of the apparatus as a unit. To attach this unit to the base I preferably strike up from the base plate 23 a lug or clamp member 24 (Fig. 2), so shaped that the yoke portion 21 of the frame will slide tightly beneath this lug 24. Thus the two legs of the frame have their yoke portions 21 slid under the lugs 24 to abut the shoulders 25. Now in order to retain the frame on the base plate I provide a locking member, shown in detail in Fig. 3, formed up of a piece of sheet metal with upwardly extending ears 26 adapted to snugly fit between the legs 20. This locking element is then secured to the frame by a pin 27 which passes through the holes 28 in the ears 26 and corresponding holes in the legs of the frame. A downwardly extending arm 29 of this locking member rests against the inner face of the lug 24. The locking member has shoulders 30 which abut the edges of the legs 20, the parts being so proportioned that with the shoulder 30 against the edges of the legs, the arm 29 must be slightly sprung to insert the pin 27 and thus the unit is securely held to the base.

To remove the unit from the base it is only necessary to withdraw the pin 27, thereby permitting a tilting of the locking element so that the arm 29 is freed of the lug 24 sufficiently to permit sliding the frame out of the lug 24 and removing it from the base plate 23.

This locking member also carries the attaching terminals for the device, being provided with an arm 31 to which an insulating plate 32 is secured by rivets 33 (Fig. 2). Terminal plates 34 are insulatingly attached to the insulating sheet 32 by suitable eyelets 35, but which rivets do not touch the

metal arm 31 which has clearance holes 36 therein, as shown in Fig. 7. These terminal plates 34 carry binding screws 37, the plates being notched at 38 to take a round terminal clip or a spade clip may be inserted between the screw 37 and plate 34.

Referring now to the diaphragm operating mechanism, this is preferably built up in a self-contained unit the parts of which are preferably supported upon a frame adjustably carried by the diaphragm carrying frame. This mechanism frame consists of an elongated U-shaped member having sides 39-40 bent up from the base portion 41. These sides 39-40 fit snugly between the legs 21 of the main frame and are adjustably held in the frame by a pivot mounting in the form of a pin 42 which passes through the frame legs and the sides 39-40. Thus the left end of the pivoted frame is free to move up and down by adjusting the screw 43. This adjusts the armature and electromagnet so as to vary the air gap. This adjusting screw 43 is threaded at its lower end 44 in the plate 41 of the frame so that as the screw 30 is rotated the frame is correspondingly moved up and down. The screw 43 carries a knurled head 45 which is outside the casing, as indicated in Fig. 1, a soft felt washer 46 being interposed between the washer 47 carried by the screw 43 and the casing so as to provide a dust-proof hole through which the screw 43 extends. This adjusting screw 43 provides a safety adjustment in that in threading the screw into the plate 41 it stops when the shoulder of the screw abuts the plate 41, limiting the adjustment in one direction. When the screw 43 is rotated in the other direction it moves the plate 41 downwardly, thereby increasing the air gap at the armature, but this adjustment is limited in that it is so proportioned that the screw threads out of the plate at the desired limit of adjustment and simply rotates against the end of the plate without any further movement thereof.

The mechanism frame is held under tension by a spring 48 secured underneath the plate 41 of the frame and resting upon a pin 49 extending through the frame legs 20.

Now as to the diaphragm operating mechanism, this is preferably in the form of a so-called direct current electromagnet, that is one in which no permanent magnet is employed. To this end I preferably provide two spools or coils preferably connected in series and made up in the form of a unit to be attached to the adjusting frame. The coils are preferably similar units, each comprising a combination core and heel piece struck up out of a single sheet of suitable metal, the core 50 being sheared up out of the body between the two fastening ears 51 and the downturned portion 52 being pro-

vided as heel pieces by which the two cores are riveted together. In building up these coils, each core element is taken separately and appropriate spool heads forced thereon, after which the wire is wound on the core. The paired spools are then fastened together by riveting the heel pieces 52 together so as to form the single unit which is then attached to the bottom plate 41 by screws 53, the spools extending up through an opening 54 in the bottom plate 41. The coils are so wound as to present opposite poles at the free or armature ends of the cores, the ends of the windings extending through the bottom heads and being connected together and to the terminals 34, as is more clearly indicated in Fig. 6. Now as to the armature, this is preferably in the form of a flat plate 55 of suitable material loosely set upon the ends of the core and pivoting from its end 55'. To hold the armature in place I provide a bracket member 56, preferably of non-magnetic material, having a forked end resting upon the edge of the end of the core and shaped so as to receive the end of the armature 55 and prevent transverse movement thereof. A pin 57 is swaged upon the end of the armature and is connected to the diaphragm 16 by a threaded link 58 having an eyelet at its lower end through which the pin 57 extends. This link 58 passes up through the diaphragm 16 and has a washer and nut on each side of the diaphragm to clamp the link preferably rigidly thereto. Suitable adjustment, of course, is given to secure proper connection between the armature and diaphragm. I then preferably place a light coating of a suitable hard wax at the connection between pin 57 and the eyelet, to provide a tight connection.

As I do not depend upon a permanent magnet to give a normal flexure to the diaphragm 16, I provide a tension spring 59 which holds the armature in operative relation to the electromagnet and also places a tension upon the diaphragm to slightly bow the same. This spring 59 is preferably adjustable and is riveted to a rocker arm 60 pivotally supported between the frame sides 39-40 by a pin 61 which is held under the rear end of the spring 59 to keep it from coming out. In order to adjust the spring 59 I provide a screw 62 threaded through the plate 41 and arm 63 of the magnet frame, the arm 63 being sprung slightly after the parts 63-40 are threaded so as to force the threads in these two parts out of normal alignment. Then when the screw 62 is threaded therein it is frictionally held by the springing of the frame. This screw 62 engages the rocker arm 60 so that as the screw is moved one way or the other the arm 60 is adjusted up and down to correspondingly adjust the tension of the spring.

59. This gives the proper tension to the armature 55 and diaphragm 16, varying according to the current applied and speaking results desired.

5 It will thus be seen that the main rocking frame carries the electromagnet and associated armature, together with the corresponding tension spring 59, so that this entire piece of apparatus may be adjusted as 10 a unit to vary the air gap of the electromagnet and the spring 59 may be independently adjusted to vary the tension on the armature and flexure of the diaphragm.

To attach the horn to the device I provide 15 a novel arrangement in the form of a cup 64 which threads into the neck of the diaphragm cup 15. The neck of the horn 65 is provided with a sleeve 66 suitably secured thereto after the lock nut 67 is placed on the 20 neck of the horn. A soft rubber washer or gasket 68 is placed in the bottom of the cup 64 and the neck of the horn inserted in the cup. The lock nut 67 is then threaded onto the cup 64, engaging the upper shoulder on 25 the sleeve 66, so as to hold the horn rigidly in place.

I also provide a novel means for securing a cap or cover over the mechanism, to this end providing the cover 69 which is formed 30 up of a suitable material and of the proper shape to enclose the apparatus, the form shown being circular. This cover 69 sets down into the upturned peripheral flange of the base plate 23, the parts being held together by passing the horn holding cup 64 through the cover and having a shoulder on the cup 64 to engage the cover and hold it in place as the cup is screwed into the diaphragm cap 15. The cover 69 is also provided with a pair of openings through which the terminal plates 34 pass, these openings each having a soft rubber bushing 70 to insulate the terminal plates 34 and prevent contact with the cover.

45 It will be noted that the adjusting screw 43 has an operating knob 45 threaded thereon on the outside of the casing 69. In order to assemble these parts in this way the knob 45 is taken off before the casing 69 is applied, 50 the terminal screws 67 also being out of the terminal plates 34 at this time. Also, of course, the cup 64 is out of the casing 69. The casing is then passed over the top of the apparatus with the adjusting screw 43 55 extending up through the casing. A pair of pliers or suitable instruments is then slipped through the opening at the top of the casing 69 to grasp the shank of the adjusting screw 43 while the nut 45 is being 60 threaded and set thereon. The nut 45 is preferably set tight enough so that it will not readily thread off in adjusting the device. The cup 64 is then passed through the casing 69 and threaded into the neck of the diaphragm cap. Also the terminal screws 37

are threaded into their plates 34. We then have a device completely enclosed and practically dust-proof and fool-proof, as when assembled in this way it is not readily discovered how to take it apart. This is most 70 desirable in connection with a piece of apparatus of this kind to keep those unfamiliar with its construction from gaining access to the interior and disturbing the proper adjustment of the parts.

75 In the use of the device after being normally adjusted it may be adjusted by simply varying the armature adjustment through the use of the exterior adjusting nut 45. This gives a range suitable for ordinary use 80 with different circuits.

What I claim as new and desire to secure by Letters Patent is:

1. In a receiver, a diaphragm and mounting therefor, an electromagnet and an armature therefor connected to the diaphragm, a spring yieldingly holding the armature under tension, means for adjusting the spring tension independent of variation of adjustment of the armature, a frame for the electromagnet pivotally supported at one end by said mounting, and means for adjusting the mounting on its pivot to move the electromagnet to vary the air gap between the armature and electromagnet.

85 2. In a receiver, a diaphragm and mounting therefor, an electromagnet and an armature therefor connected to the diaphragm, a frame for the electromagnet pivotally supported at one end by said mounting, a spring 90 adjustably carried with the frame acting upon the armature to press it toward the electromagnet and flex the diaphragm, and means for adjusting the mounting on its pivot to move the electromagnet to vary the air gap between the armature and electromagnet.

95 3. In a receiver, a diaphragm and mounting therefor, an electromagnet and an armature therefor connected to the diaphragm, a frame for the electromagnet pivotally supported at one end by said mounting, a spring 100 adjustably carried with the frame acting upon the armature to press it toward the electromagnet and flex the diaphragm, and means for adjusting the mounting on its pivot to move the electromagnet to vary the air gap between the armature and electromagnet and vary the spring pressure on the armature and diaphragm.

110 4. In a receiver, a diaphragm and mounting therefor, an electromagnet and armature therefor connected to the diaphragm, an elongated frame for carrying the electromagnet pivotally supported at one end by 115 said mounting and an adjusting screw connected to the other end of the frame for tilting the frame on its pivot to vary the air gap between the armature and electromagnet, said adjusting screw and mounting 120 125 130

cooperating to limit the extent of adjustment of the frame in both directions.

5. In a receiver, a diaphragm operating electromagnet and armature, a sheet metal frame for the electromagnet, an armature tension spring carried by said frame, said frame having two relatively yieldable plates tipped in a normal relation and then sprung to an abnormal relation, and an adjusting screw for the tension spring threaded through the frame plates while sprung back to a nominal position to frictionally hold the adjusting screw in a set position.

6. In a receiver, a diaphragm and supporting cup therefor, and operating mechanism for the diaphragm comprising an elongated U-shaped frame pivotally attached at one end to the supporting cup and having an adjusting screw operatively connected to the other end so as to adjust the frame toward and away from the diaphragm, an electromagnet secured to the base of the frame between its sides, and an armature for the electromagnet pivotally supported at one end and having its other end connected to the diaphragm.

7. In a receiver, a diaphragm and supporting cup therefor, and operating mecha-

nism for the diaphragm comprising an elongated U-shaped frame pivotally attached at 30 one end to the supporting cup and having an adjusting screw operatively connected to the other end so as to adjust the frame toward and away from the diaphragm, an electromagnet secured to the base of the 35 frame between its sides, an armature for the electromagnet pivotally supported at one end and having its other end connected to the diaphragm, and an armature spring and carrying plate therefor pivotally supported between and by the sides of the frame.

8. In a receiver, a diaphragm operating electromagnet consisting of twin coils each having a sheet metal combination core and heel piece comprising a flat core struck up 45 leaving two right angle ears extending to one side of the core and a portion of the sheet metal extending from the other side of the core and then bent downwardly to form a heel piece, said down turned portions 50 of a pair being turned toward each other and permanently secured together to form a unitary structure.

In witness whereof, I hereunto subscribe my name this 8 day of July, 1924.

SAMUEL E. WITT.
